**COMPOSITE CONSTRUCTION FOR DISTRIBUTOR
COMPONENTS**

William McCandless, Toledo, Ohio, assignor to John Erler Industries, Inc., Toledo, Ohio, a corporation of Ohio

Filed Nov. 13, 1962, Ser. No. 237,269
5 Claims. (Cl. 200—19)

This invention relates to a distributor and more particularly to details of construction of a cam, points, and rotor of a distributor.

Distributors have remained substantially unchanged for the last twenty to thirty years, probably because they have been relatively satisfactory, being reasonably reliable, producing satisfactory results, and not requiring excessive maintenance. There are, however, several aspects of distributors as presently known, upon which improvements can be made. For one thing, distributors presently are quite expensive and especially so when it is considered that a one cent to two cent savings in the overall cost of an automobile is considered of the utmost importance to automobile manufacturers. Distributors also tend to be somewhat sluggish at times during rapid acceleration or deceleration, due to the inertia of some of the comparatively heavy rotating parts therein.

The present invention relates to a new distributor construction which achieves several advantages, a principal one of which is a substantial reduction in the cost of the distributor. The new distributor construction also achieves a substantial reduction in weight and thus enables the distributor to be more responsive to sudden changes in speed and thereby achieve better engine performance.

A distributor according to the principles of the present invention embodies a circuit breaker cam made of a non-metallic, plastic material which is functionally integral with a bushing which constitutes a sleeve bearing for the cam. The cam also has an extension above it which directly supports a rotor of the distributor. The new distributor also is characterized by a breaker arm having a metal cam follower rather than the usual plastic or fiber one heretofore employed. The plastic circuit breaker cam and related parts, along with the simplified design of the cam and rotor, reduces the weight of these parts to approximately one-sixth of the weight of the corresponding components of conventional distributors as now known in the art. This weight reduction improves engine performance by reducing the sluggishness or lag heretofore inherent in distributor operation due to the weight of the rotating parts. The reduction in weight of these parts also enables smaller and lighter governor weights to be used which again increases the response of the distributor.

Of more importance perhaps, is the substantial cost reduction brought about by the new construction. The one-piece construction of the cam and rotor extension reduces the number of parts in the distributor and thereby reduces assembly time. Because a plastic extension is used to connect the cam and rotor, the rotor itself can be of simpler construction, not requiring the usual heavy plastic rotor support heretofore needed to achieve proper insulation between the contact arm of the rotor and the metal shaft supporting it. This further reduces manufacturing cost and weight. Because the governor weights can be smaller and lighter, they can be blanked from metal stock, such as $\frac{1}{8}$ inch metal stock for many distributors, which further reduces the manufacturing costs of the weights. These weights at the present are sufficiently thick that they usually are made by a sintering technique which is the least expensive way of producing them in most instances. Because the governor weights are lighter, the springs holding them in their inner positions

2

also can be smaller and less expensive. As a combined result, the cost of the distributor can be reduced about fifty to seventy cents.

The molded plastic cam has an additional advantage in that its shape is not limited as has been heretofore necessary with metal cams which must be ground, with the final shape thereof being subject to the limitations of the grinding operation. Further, with the plastic cam and metal follower combination, less wear is encountered on all components. The cam normally is subject to less wear than the follower because the cam has a number of high points or lobes which wear whereas the follower has only one wear point. For a six cylinder engine, the follower receives six times the wear of the cam because the follower engages six lobes during one revolution of the cam whereas each lobe only engages the follower once during each revolution. Thus, the use of the metal follower and plastic cam places the wear resistance where it should be.

It is, therefore, a principal object of the invention to provide an improved distributor having the advantages outlined and discussed above.

Other objects and advantages of the invention will be apparent from the following detailed description of a preferred embodiment thereof, reference being made to the accompanying drawing, in which:

FIG. 1 is a view in vertical cross section of a distributor embodying the principles of the invention, with breaker points and a rotor thereof being offset from their normal positions for purposes of illustration;

FIG. 2 is a view in cross section taken along line 2—2 of FIG. 1 and showing in particular a circuit breaker cam and breaker contact points embodying the invention;

FIG. 3 is a horizontal view in cross section taken along the line 3—3 of FIG. 1 and showing the rotor construction of the new distributor;

FIG. 4 is a view in horizontal cross section taken along the line 4—4 of FIG. 1 and showing the construction of the governor weights of the distributor, and

FIG. 5 is a view in perspective of the rotor design.

Referring to the drawing, and more particularly to FIG. 1, a distributor indicated at 10 functions substantially the same as most conventional distributors now known in the art. It can be divided into several assemblies, including a circuit breaker assembly indicated at 12, a governor assembly indicated at 14, and a rotor assembly indicated at 16. Each assembly operates in the same manner as the corresponding assembly of a conventional distributor.

Referring to the circuit breaker assembly 14, a timer shaft 18 extends upwardly through a lower metal housing 20 of the distributor 19, with the timer shaft 18 being driven through a gear 22 in the usual manner to cause the shaft to rotate in a fixed relationship with respect to the engine crankshaft. In this instance, the timer shaft 18 includes an upper spindle or axle 24 upon which a circuit breaker cam 26 rotates. The cam 26 actually consists of two parts, an outer sheath 28 forming the contour of the cam with the usual dwell portions 30 and lobes 32 (FIG. 2), and a metal inner bushing 34 fixedly mounted therein, preferably at the time the cam member 26 is molded. The bushing 34 preferably has a knurled outer surface to provide secure engagement with the sheath 28 which is of plastic, for example, nylon or "Delrin." The combination metal and plastic construction of the cam 26 is preferred to a cam made entirely of plastic because closer dimensional tolerances can be attained with the combination than with a solid plastic cam which tends to shrink non-uniformly.

It will be noted that the steel bushing 34 constitutes at least half the thickness of the overall cam wall with the sheath 28 making up the remaining portion.

Around the cam 26 is a horizontal partition or base plate 36 upon which is pivotally mounted a circuit breaker plate 38 which carries a circuit breaker arm 40 supported on the plate 38 by a pivot pin 42. The circuit breaker arm 40 includes a circuit breaker contact or point 44 which is connected to a metal strip 46 which also forms a metal cam follower 48. In this instance, the metal strip 46 also is bent around and behind the arm 40 to act as a return spring for the arm and to provide electrical contact with a terminal 50 which is suitably connected to the usual primary winding of the ignition coil. The metal strip 46 is backed up by a plastic breaker arm body 52 which is mounted on the pivot pin 42 and insulates the strip 46 from the pin 42 and the plate 36. The metal cam follower 48 can also be formed in other ways, as by being a separate piece attached directly to the body 52.

The contact 44 makes and breaks with a stationary contact 54 in the usual manner as the breaker arm 40 moves back and forth due to the engagement of the metal follower 48 with the plastic cam sheath 28. This makes and breaks the circuit through the primary winding and in turn induces a large voltage in the secondary winding. The secondary coil is connected to a central terminal or socket 56 in an upper insulating housing 57 of the distributor. The central terminal 56, in turn, is electrically connected through a rotor indicated at 60 of the rotor section 16 to individual peripheral terminals 58, each of which is connected to a hot terminal of a spark plug. The circuit breaker assembly 14 induces the high voltage and the rotor assembly 16 directs this voltage to a particular spark plug.

The rotor 60 in this instance simply comprises a metal strip forming a resilient contact arm 62 and an outer conducting arm 64 with a contact point 66. The arm is attached directly to an upper end of a cam extension 68 which is structurally integral with the cam sheath 28 and extends concentrically upwardly therefrom. The rotor 60 can be detachably mounted on ears 70 of the extension 68 to facilitate assembly of the distributor components.

The rotor 60 carries a high voltage and therefore must be well insulated from any metal parts other than the terminal sockets 56 and 58. In the usual distributor which has a metal shaft extending up to a point close to the rotor, insulation must be provided by a heavy insulating arm constituting part of the rotor and upon which the metal conducting strip is mounted. Because there is no metal in the present distributor closer than the bushing 34, the entire insulating arm can be dispensed with and the connecting strip constituting the rotor 60 merely mounted on the upper end of the extension 68, which is a substantial factor in reducing the overall weight as well as the cost of the distributor.

The governor section 14 advances the spark or the point at which the contacts 44 and 54 make and break by rotating the cam 26 slightly further in the direction of rotation when the speed of the engine increases. The governor section 14 includes two weights 72 which are pivotally mounted by pins 74 on a governor plate 76 which is affixed to the shaft 18 and rotates therewith. The free ends of the weights 72 are connected to springs 78 which in turn are connected to projections 80 forming part of the plate 76. The springs 78 restrain the weights from outward movement until the shaft reaches a predetermined speed. The weights 72 have the usual pins 82 projecting upwardly therefrom which extend into slots 84 of a governor arm 86, with the pins causing rotation of the arm 86 as they swing outwardly. The arm 86 in this instance is structurally integral with the cam sheath 28 and causes the cam 26 to rotate slightly in a clockwise direction on the axle 24 as the weights swing outwardly.

Because of the lighter weight of the rotating components of the distributor, the governor weights can be

much thinner than heretofore and can be blanked from $\frac{1}{8}$ inch stock for many distributors, in place of the usual comparatively expensive sintering operation which constitutes the least expensive way of making the weights in most instances in standard distributors.

A vacuum attachment (not shown) is mounted on the lower housing 20 and has an arm (not shown) connected to the breaker arm plate 38 to cause the plate 38 to move relative to the base plate 36 and also relative to the cam 26. This retards the spark during acceleration and is the same as those vacuum units employed in standard distributors. Hence, and for clarity of illustration, it is not shown at all in the drawings and will not be discussed further in the specification.

From the above, it will be seen that the distributor 10 basically functions the same as any conventional distributor with the circuit breaker section 12 making and breaking the circuit to a primary winding of a coil in order to produce high voltage for a spark plug, the particular spark plug being controlled by the rotor section 16. The governor section 14 also operates in the usual manner to advance spark during increased engine speed and the vacuum unit (not shown) is employed to retard the spark during periods of acceleration and the like.

Otherwise, the distributor 10 is substantially different from conventional distributors. The combination plastic sheath 28 and metal bushing 34 enable the cam 26 to have closely held dimensional tolerances and yet reduce the weight of the cam, particularly the outer portion thereof where the inertia is the greatest. The plastic extension 68 which is integral with the sheath 28 also is much lighter than the usual metal shaft heretofore used and extending through the cam, and further provides savings by simplifying the construction of the rotor 60. The usual heavy insulating rotor arm is completely eliminated, as previously pointed out, which reduces production costs and further reduces weight. The governor weights 72 can be thinner and less expensive, because of the lesser weight and inertia of the other rotating components. All of these features contribute to a lighter distributor which achieves improved performance and is substantially less expensive than those heretofore known. The shape of the plastic cam also no longer need be unduly restricted to the extent heretofore necessary when the cam was made of metal and was ground. Further, by employing the plastic cam and the metal follower point, the problem of wear is substantially reduced.

Various modifications of the above described embodiment of the invention will be apparent to those skilled in the art and it is to be understood that such modifications can be made without departing from the scope of the invention, if they are within the spirit and tenor of the accompanying claims.

I claim:

55. 1. In a distributor including a housing, a timer shaft extending into said housing, a circuit breaker cam rotatably mounted on said shaft, a circuit breaker arm adjacent said cam and having a follower engaging said cam to cause pivotal movement of said arm, a rotor above said cam and rotatable therewith, and a governor assembly controlling the position of said cam, the improvement comprising said circuit breaker cam including a metal bushing supported on a portion of said shaft for rotatable movement with respect thereto, and a plastic sheath around said bushing and functionally integral therewith, said bushing being at least as thick as said plastic sheath so as to constitute at least half the thickness of the overall cam wall, said plastic sheath forming the outer surface of the cam.
60. 2. In a distributor including a housing, a timer shaft extending into said housing, a circuit breaker cam rotatably mounted on said shaft, a circuit breaker arm adjacent said cam and having a follower engaging said cam to cause pivotal movement of said arm, a rotor above said cam and rotatable therewith, and a governor assem-

bly controlling the position of said cam, the improvement comprising the other surface and not more than half the thickness of the wall of said circuit breaker cam being of a plastic material, the remaining thickness of said wall constituting a metal bushing on said shaft, the height of said bushing not exceeding the height of said cam and the follower of said circuit breaker arm being of metal.

3. In a distributor including a housing, a timer shaft extending into said housing, a circuit breaker cam rotatably mounted on said shaft, a circuit breaker arm adjacent said cam and having a follower engaging said cam to cause pivotal movement of said arm, a rotor above said cam and rotatable therewith, and a governor assembly controlling the position of said cam, the improvement comprising said circuit breaker cam including a metal bushing rotatably supporting said cam on said shaft and a plastic sheath functionally integral with said bushing and forming a plastic cam surface, a plastic extension extending upwardly from said plastic cam sheath, and said rotor being attached directly to the upper end of said extension.

4. In a distributor including a housing, a timer shaft extending into said housing, a circuit breaker cam rotatably mounted on said shaft, a circuit breaker arm adjacent said cam and having a follower engaging said cam to cause pivotal movement of said arm, a rotor above said cam and rotatable therewith, and a governor assembly controlling the position of said cam, the improve-

ment comprising said cam having a plastic sheath forming a plastic cam surface, a plastic extension extending upwardly from said cam sheath, and said rotor being attached directly to the upper end of said extension and consisting essentially of an elongate strip of electrically conducting material.

5. In a distributor including a housing, a timer shaft extending into said housing, a circuit breaker cam rotatably mounted on said shaft, a circuit breaker arm adjacent said cam and having a follower engaging said cam to cause pivotal movement of said arm, a rotor above said cam and rotatable therewith, and a governor assembly controlling the position of said cam, the improvement comprising said cam including a metal bushing supported on said shaft for rotatable movement, and a plastic sheath functionally integral with said bushing and forming an outer cam surface, said breaker arm having a metal follower for engaging said plastic cam surface, a plastic extension extending upwardly from said cam sheath, and said rotor comprising an elongate electricaly-conducting member removably attached directly to the upper end of said extension.
